DESIGN FOR A LIGHTER

Alfredo W. Doux, New York, N. Y., assignor to Snap-Lite Corporation, New York, N. Y., a corporation of New York

Application December 29, 1945, Serial No. 125,206

Term of patent 3½ years

(Cl. D48—27)

To all whom it may concern:

Be it known that I, Alfredo W. Doux, a citizen of the Republic of Brazil, residing at New York, in the county and State of New York, have invented a new, original, and ornamental Design for a Lighter, of which the following is a specification, reference being made to the accompanying drawing, forming a part thereof.

Fig. 1 is a front view of a lighter, showing my new design;

Fig. 2 is a top view thereof;

Fig. 3 is a side view thereof; and

Fig. 4 is a bottom view thereof.

I claim:

The ornamental design for a lighter, substantially as shown.

ALFREDO W. DOUX.
